Inventor:

Christopher Day

United States Patent Office.

CHRISTOPHER DAY, OF MINERAL POINT, WISCONSIN.

Letters Patent No. 97,765, dated December 14, 1869; antedated November 30, 1869.

IMPROVED MACHINE FOR CRIMPING AND FORMING THE FRONTS OF BOOTS.

The Schedule referred to in these Letters Patent and making part of the same.

To all whom it may concern:

Be it known that I, CHRISTOPHER DAY, of Mineral Point, in the county of Iowa, in the State of Wisconsin, have invented a new and improved Machine for Crimping and Forming the Fronts of Boots; and I do hereby declare that the following is a full and exact description thereof, reference being had to the accompanying drawings, and to the letters of reference marked thereon.

The nature of my invention consists in a machine, in duplicate, for the purpose of crimping and forming the fronts of boots; and I hereby proceed to describe its construction, reference being had to the machine as single only.

The frame F F, with upright centre-pieces c c, ratchet-beam B, with lever L attached, ratchet-bar R, connected with gate g, which gate works upon roller-guides, and is actuated by means of the lever L, ratchet-beam B, and ratchet-bar R.

Immediately beneath and in the gate g, is a groove, for the purpose of receiving the "crimp-board," Figure 2, which "crimp-board" is secured in the groove of the gate by means of screws s s or springs placed within the groove.

Immediately beneath the gate g is fixed a stanchion, o, in two sections, (adjustable by screw N,) with convex surface.

The upper portion of the stanchion-sections, and around the convex margin, are prepared interspaces, which are closed by means of pinion-teeth upon the supplemental jaws K K, which jaws work upon hinges, and are adjusted or loosed by means of screws T T.

The utility of the marginal interspaces in the sections of the stanchions, is to allow the insertion of clasps, to be placed upon the "crimp-board" when forced between the sections of the stanchion, thereby securing the leather thereto, while it is being removed from the machine.

The pinion-teeth of the supplemental jaws K K are for the purpose of filling the interspaces in the sections of the stanchion, to afford an even and smooth surface to the convex portion of the stanchion while the machine is operating.

To enable others skilled in the art to make and use my invention, I will proceed to describe its construction and operation.

It consists in a square frame, F F, with two upright centre-pieces c c, and gate g, working upon roller-guides, or sliding in grooves.

The gate contains grooved receptacles beneath, in which to place the "crimp-board," fig. 2, which is secured by screws s s, or springs, in the proper position.

The gate g is actuated by means of ratchet-bar R, attached to the upper portion of the gate g, in connection with ratchet-beam B and lever L, attached to ratchet-beam; the stanchion o, in two sections, resting in frame immediately beneath the gate, and having convex surface, corresponding with the concavity of the "crimp-board," fig. 2.

The two sections of the stanchion o are adjusted by means of screw and nut N.

Two supplemental jaws, K K, are fixed, one to each section of the stanchion, and working upon hinges, and containing pinion-teeth fitting into interspaces of the sections of the stanchion.

The leather, or front of the boot, is placed upon the convex surface of the stanchion o, the lever L brought down, which brings the "crimp-board," fig. 2, in contact with the leather, and forces it between the two sections of the stanchion o, and fixes it firmly upon the "crimp-board," fig. 2, (now in the groove of the gate g.) The supplemental jaws K K are then loosed, by means of screws T T, and dropped down, revealing the interspaces in the sections of the stanchion, and in which are placed clasps for the purpose of securing the leather upon the "crimp-board," prior to removing it from the machine.

What I claim as my invention, and desire to secure by Letters Patent, is—

The new and improved method of forming and crimping the fronts of boots, by means of the ratchet-beam B and ratchet-bars R R, in combination with the gates g g, stanchions o o, and toothed jaws K K, and the adjustment of the stanchion-sections and jaws K K, by means of screws N and T T, constructed and arranged as herein described.

CHRISTOPHER DAY.
